UNITED STATES PATENT OFFICE

159,142

COMBINATION FISHLINE AND HOOK KIT

Julian T. Crandall, Ashaway, R. I., assignor to
Ashaway Line & Twine Mfg. Co., a corporation
of Rhode Island

Application June 19, 1947, Serial No. 139,815

Term of patent 3½ years

(Cl. D31—4)

To all whom it may concern:

Be it known that I, Julian T. Crandall, a citizen of the United States, residing at Ashaway, in the county of Washington and State of Rhode Island, have invented a new, original, and ornamental Design for a Combination Fish Line and Hook Kit, of which the following is a specification, reference being had to the accompanying drawing, constituting a part hereof:

Fig. 1 is a perspective view of the combination fish line and hook kit showing my new design; and

Fig. 2 is an end view thereof.

I claim:
The ornamental design for a combination fish line and hook kit, substantially as shown.
JULIAN T. CRANDALL.
